UNITED STATES PATENT OFFICE

ARTHUR O. AUSTIN, OF BARBERTON, OHIO, ASSIGNOR, BY MESNE ASSIGNMENTS, TO THE
OHIO BRASS COMPANY, OF MANSFIELD, OHIO, A CORPORATION OF OHIO

WOOD SUPPORT FOR CONDUCTORS

Application filed June 1, 1926. Serial No. 112,744.

This invention relates to wood structures or poles for supporting transmission lines or other conductors and has for its object the provision of means for taking advantage of the insulating characteristics of the wood structure while preventing injury to the wood by leakage currents, discharges, lightning or other causes to which such structures have heretofore been subjected.

10 The invention is exemplified in the combination and arrangement of parts shown in the accompanying drawings and described in the following specification and it is more particularly pointed out in the appended 15 claims.

In the drawings—

Fig. 1 is an elevation of a pole structure having one embodiment of the present invention applied thereto.

20 Fig. 2 is a view similar to Fig. 1 showing the invention applied to a somewhat different arrangement of the parts carried on the pole.

In transmission work it has long been 25 known that the insulation in an ordinary wood pole is frequently sufficient to prevent flash-over during lightning and eliminates much bird trouble. The frequent shattering of poles during electrical storms as well as 30 the burning of poles has caused its use to be abandoned in many cases, although the danger of arcs to ground has been increased by going to a metal structure or the conversion of the pole to the equivalent of a metal structure by use of a ground wire or ground leads 35 running down the pole. If the insulation furnished by a wood pole can be made use of without danger of shattering, the effective insulation of even a moderate voltage line may 40 be much higher than that of even the highest voltage line using grounded metal structures.

Fig. 1 shows a transmission pole having a body 10 upon which are mounted cross-arms 11 and 12. The conductors 13 are carried by 45 insulators 14 which are attached to the cross-arms by pins 15. The sky wire 16 is shown mounted on an insulator and pin 17 and 18. The pole is also equipped with an arcing rod 19 which is connected to the braces 20. A sky 50 or charging wire 16 may be tied in directly

to the down lead or jumper 19 or it may be connected only in case a discharge takes place across the gap 21. During electrical storms the line may be struck by lightning or the release of a bound charge may set up a very 55 high potential or voltage in the conductors 13 which will cause arcing to braces 20 or a flash-over of the insulators if they are mounted on a grounded structure. Since the sky wire or charging wire 16 will have approximately 60 the same voltage induced on it at the time of release of a bound charge as that induced upon the conductors 13 the electrical charge on this conductor may be used to charge up the structure, thereby reducing the 65 difference in potential between the conductors 13 and the conducting parts 19 and 20 of the supporting structure. This, however, can only take place when the jumper or 70 lightning rod 19 is not grounded and there is 75 an insulating section in the supporting structure in the path to ground.

In most cases, the sky or charging wire 16 is not necessary as the structure may be charged by the lightning rod 19 so that the 80 difference in potential between the conductors 13 and the structure will be little more than that produced by the normal operating voltage. Where the lightning rod 19 is used 85 it is necessary that this terminate preferably near the top of the structure. If this member terminates close to the side of the structure there is danger that it will discharge into the pole or structure or that an arc from the end will burn the structure. The lightning rod 19 should be such that it will shunt the section of the pole so that discharge cannot 90 take place inside the pole and shatter same. In order to insure safe operation it is necessary, however, that considerable care 95 be given to the lower end of this member which should preferably terminate in a discharge member which will screen the pole. The lower end should preferably terminate in one or more flaring members 22 whose 100 distance from the pole increases as they proceed in the general direction of the pole. Where this is carried out properly a discharge will start from the lower end of the member 22 under a stroke of lightning or a 105

heavy induced charge and will not affect the pole. This discharge will go to ground or a corresponding member 23 which is grounded may be placed below so that the discharge will take place between the members 22 and 23. In general, a distance between the members 22 and 23 of from 1 to 4 feet will require for arcing a voltage equivalent to that of flash-over of the usual range of insulators found in transmission practice. The gap between the members 22 and 23 tends to increase the effective insulation between conductors and ground over the effective insulation where the rod 19 is directly grounded by a low resistance conductor and in favorable cases the effect of the gap is equivalent to increasing the insulation for the conductor by the resistance to flash-over voltage of the gap. This is particularly true for high frequency disturbances.

Where the wood structures and arrangements of conductors are such that the lightning rod 19 will not sufficiently charge up the structure, this charging may be supplemented by the sky or counter E. M. F. wire 16. If this is tied directly into the down lead 19 there is danger that a bird or squirrel may produce a short circuit. If, however, it is insulated and connection to ground is only made through a gap 21 it does not reduce the effective insulation of the system for birds or squirrels. Where the sky wire, is not sectionalized, it is advisable to insulate it, otherwise multiple paths to ground at the various structures will make it possible for a bird or squirrel to start a short circuit by shunting an insulator supporting a conductor wire 13.

In many cases leakage and charging current over the insulators has caused burning of the wooden structure and made it necessary to do away with the insulator furnished by the wood structure. This, however, may be taken care of with the improved construction. Where leakage conditions are severe, the insulator supports 15 may be bonded together by conductors 24. In general, the leakage and charging current will be equalized for most systems. In some cases, however, due to a faulty insulator or greater leakage owing to a lower surface resistance or difference in location of the conductor, there may be an unbalanced current or voltage which will cause burning of the wood structure in going to ground. In order to prevent damage to the insulating zone of the pole this section is shunted by a resistance member 25. The resistance 25 may be made up in any suitable manner depending upon the degree of resistance necessary. Where conditions are such as to cause heavy unbalanced leakage over the insulators, it may be advisable to use a rather low resistance. In general, however, a resistance of several thousand ohms will carry away the unbal-

anced current. A resistance of this magnitude will have a very high IR drop in the case of high frequency discharge or in the case of impact or the release of a bound charge as with lightning. These resistances may be made with a higher resistance wire placed in an insulating tube filled with a non-corrosive electrolyte or oil. For the higher resistances an insulating tube may be used of proper cross-section filled with water and alcohol or other suitable mixture which will not freeze and damage the tube.

In case the line is grounded by the conductor falling on a metal arm 20 or through the insulator puncturing, the resistance, if high, will not withstand the discharge for any considerable length of time. In this case, however, it will usually evaporate the conducting fluid and may clear the line until such time as repairs can be made. In many cases the resistance member, however, can be so proportioned that it will operate the circuit breaker and clear the line so that there will be no danger of destroying the structure. Many different applications are possible making use of the principles involved. In general, it is desired to have the lightning or the bound charge raise the voltage of the metal parts at the top of the structure so that the difference in potential between the conductors and the supporting members will not be sufficient to cause the insulators to flash-over. This may be aided by the use of a lightning rod or antenna projecting well above the conductors or by a charging or static wire. Where these are not used the electrostatic capacity between the conductors 13 and the upper portion of the supporting structure must be sufficient so that the potential of this portion of the supporting structure will be raised by the disturbing charge sufficiently to counteract the increase in the stress between the conductor 13 and their supports.

In a system where the insulators are mounted on metal arms on a wood pole, the bonding may be already affected by the cross-arms. A common arrangement of this type is shown in Fig. 2.

In the form shown in this figure a wood pole 26 is provided with cross-arms 27 and braces 28. Insulators 29 are mounted on pins 30 supported by the cross-arms and braces. The metal supporting parts attached to the insulators are connected by jumpers 31. The pole has an insulating zone 32 located below the cross-arms. This insulating zone is protected by the screen and discharge points 33 and 34. The screen 34 is connected to ground by a jumper 35. A shunting resistance 36 may be provided to take care of unbalanced leakage conditions. This resistance protects the insulated zone 32 from burning as previously explained. If a part or all of the insulators 29 are shunted by a bird or squirrel

so that a discharge can take place between the conductor 37 and the cross-arm 27, a power arc is likely to result if the metal arms are grounded in the ordinary way by a conductor running down the pole. Where the arms are grounded in the ordinary way by a conductor running down the pole, it is evident that a voltage which will cause an arc to strike from the conductor 37 to the cross-arm 10 or the supporting pin 30 is likely to result in a power arc.

The construction shown in Fig. 2 reduces, if not entirely eliminates, the danger of power arc for most operating conditions. Where 15 the insulated section 32 has a high resistance, a bird shunting the insulator may not draw enough current to cause a heavy power arc to pick up so that although a slight discharge may be started there would be no interruption. Where the resistance 20 is high, the amount of current which can be drawn will be limited and in some cases, even though a power arc starts, the resistance may be depended upon to clear the arc and reestablish 25 service. Where the resistance of the pole is low enough or it is impregnated or painted with a low resistance material, no shunting resistance 36 is necessary to prevent burning due to unbalanced leakage. It is evident 30 that a series of gaps rather than a single gap may be used to protect the pole. Where the screening action is sufficient and the distance between the ends of the members 33 and 34 is reduced so that a discharge will take place 35 across their ends before discharge will take place along or through the pole, it will be effectively protected from shattering during electrical storms and at the same time the insulated zones will add materially to the insulation to ground and prevent flash-over between conductor and arm.

Where the insulating section 32 is sufficient to prevent an arc to ground, a discharge between the conductor 37 and the cross-arm 45 will do no damage, for as soon as the cross-arm and conductor are raised to approximately the same potential, the arc will die out. This is particularly true where the resistance to ground is high. If, on the other 50 hand, conductors on different phases flash to the arm at the same time, a short circuit will usually result regardless of the insulation to ground. It is evident that as the potential 55 difference between the conductor 37 and the cross-arm 27 or pin 30 becomes less, the danger of flash-over will be reduced. The release of a bound charge due to the discharge of a cloud overhead will produce a high momentary voltage on the conductors 37. A portion of this charge will be transferred to the cross-arms owing to the electrostatic capacity of the insulator. This will result in 60 a voltage drop across the insulating section 85 of the pole. In general, however, the elec-

trostatic capacity of the metallic portion of the structure to ground is too high to get the best results. This is further aggravated by leakage through the resistance element 36, particularly where the latter is relatively low 70 to take care of heavy leakage on the insulators. If the charge on the cross-arms can be increased so as to raise the potential at the same time as the maximum potential exists on the conductors 37, it is evident that the condition will be improved. This may be 75 materially improved by using a static or charging wire 38 mounted on an insulator 39. The pin 40 supporting the insulator is bonded to the cross-arms by a jumper 31. By giving this insulator a relatively high electrostatic capacity the static wire 38 will tend to raise materially the potential of the metallic structure supporting the insulators. In 80 this case the static wire 38 can be made use of to equalize the potential on the supporting structure and the conductor, but since there is no direct contact between the metallic structure and the upper part of the pole, there will be no direct path to ground through the static wire in case an insulator flashes-over due to an abnormal surge or due to shunting of the insulator by a bird or squirrel. The static wire 38 can be sectionalized between 85 supporting structure so that a large or small section will be available for charging the pole, as desired, or it may run the entire length of the system without grounding or ground occasionally. While the static wire 90 will tend to keep down the bound charge used 95 in the manner shown, it will tend to charge the section of the structure above the insulating zone and thereby tend to reduce the difference in potential between the conductor 100 and supporting structure which tends to 105 cause an arc to ground.

I claim—

1. In combination, a wood pole having an insulator supported near the top thereof, a transmission line carried by said insulator, a lightning rod projecting above said pole and insulated from said transmission line and a discharge member connected with said lightning rod near the top of said pole, said discharge member being inclined gradually 110 away from said pole and terminating at a point spaced away from the surface of said pole and a grounded member forming an arcing gap from said point to ground.

2. A conductor support comprising a wood pole, an insulator mounted on said wood pole, a transmission line carried by said insulator, a lightning rod projecting above said pole, a conductor connected with said lightning rod and shunting a portion upon the top of 115 said pole and a high resistance leakage conductor connecting said lightning rod with ground the resistance of said leakage conductor being sufficiently great to provide a leakage path to ground from said conductor hav- 120 125 130

ing a conductivity commensurate with that of the leakage path from said transmission line to ground.

3. A conductor support comprising a wood pole, an insulator mounted on said pole near the top thereof, a transmission line carried by said insulator, a lightning rod carried by said pole and projecting above the top thereof and insulated from said transmission line, 10 a conductor connected with said lightning rod and shunting a portion of the top of said pole, an arcing horn connected with said lightning rod and inclined outwardly away from the surface of said pole for directing 15 an arc to ground away from said surface a grounded member forming with said horn an arcing gap and a high resistance leakage conductor extending from said lightning rod to ground.
- 20 4. A conductor support comprising a wood pole having cross-arms thereon, insulators mounted on said cross arms, transmission lines carried by said insulators, metallic members mounted on said pole adjacent said 25 transmission lines but insulated therefrom, a lightning rod extending upwardly from said metallic members and shunting a portion of said pole adjacent said conductors, said pole having an insulating section below said lightning rod and a high resistance leakage path shunting said insulating section the resistance of said leakage path being great enough to retard the escape thereover of an abnormal charge on said metallic members sufficiently that the time required for such escape is approximately that required for a like charge on said transmission line to become dissipated.

5. A conductor support comprising a wood pole, an insulator mounted on said pole near the top thereof, a transmission line carried by said insulator, a lightning rod connected with said pole and extending above the top thereof but insulated from said transmission line and from ground and shunting a portion of the top of said pole, said pole having an insulating section below said lightning rod, means for directing the discharge over said insulating section away from the surface thereof and a high resistance leakage path shunting said insulating section.

6. A wood pole having an insulator mounted thereon, a transmission line carried by said insulator, a charge receiving element mounted on said pole adjacent said transmission line but insulated therefrom, a charging conductor mounted on said pole and insulated from said charge receiving element and means forming a discharge gap 60 between said charging conductor and charge receiving element.

7. A conductor support comprising a wood pole, a plurality of insulators mounted on said pole, a metallic element mounted on said pole adjacent said insulators, transmission

conductors carried by said insulators, a charging conductor mounted on said pole, means forming a discharge gap between said charging conductor and metallic element and means for directing discharge from said metallic element away from the surface of said pole.

8. A transmission line support comprising a wood pole having cross-arms thereon, insulator pins secured to said cross-arms, insulators mounted on said pins, transmission conductors mounted on said insulators, means for electrically connecting said insulator pins said connecting means and pins being insulated from ground and a high resistance leakage conductor extending from said connecting means to ground, the resistance of said leakage conductor being sufficient to retard escape of an abnormal charge from said connecting means for a period commensurate with that required for the escape of a similar charge from said transmission conductor.

9. A transmission line comprising a wood pole having cross-arms thereon, pins mounted on said cross-arms, insulators carried by said pins, transmission conductors mounted on some of said insulators, a charging line mounted on one of said insulators, means for electrically connecting said insulator pins, an arcing member spaced from said pole and connecting with said pin connecting means a grounded member forming an arcing gap from said arcing member to ground and means forming an arcing gap between 95 said charging conductor and pin connecting means.

10. A transmission line support comprising a pole having cross-arms mounted thereon, insulators mounted on said cross-arms, a lightning rod extending above said pole, transmission line conductors carried by a portion of said insulators, a charging conductor carried by one of said insulators, means for forming a discharge gap between 105 said charging conductor and lightning rod, a high resistance leakage conductor connected with said lightning rod and bridging a portion of said pole and arcing horns also bridging a portion of said pole.

11. In combination, a wood pole, a pair of cross-arms mounted on said pole, metallic braces for said cross-arms, insulator pins carried by said cross-arms, insulators mounted on said pins, three transmission line conductors carried by respective insulators on said pins, a charging conductor carried by a fourth insulator, a lightning rod mounted on said pole and projecting above the top thereof, said lightning rod, 115 braces and insulator pins being electrically connected, arcing horns forming a discharge gap between said charging conductor and the connecting metallic parts on said pole, discharge horns gradually inclined out- 120

wardly from said pole and forming an arcing gap from said metallic parts to ground in spaced relation to the surface of said pole and a high resistance leakage conductor 5 shunting the portion of said pole.

12. In combination, a wood pole, an insulator mounted thereon, a transmission line carried by said insulator, a lightning rod mounted on said pole, a charging conductor 10 mounted on said pole, a metallic charge receiving member mounted on said pole in the vicinity of said conductor but insulated therefrom and from ground and connected with said lightning rod, means forming a 15 discharge gap between said conductor and metallic member, means forming a leakage path of several thousand ohms resistance between said metallic member and ground, and a discharge gap spaced from said pole and 20 arranged parallel with the high resistance portion of said leakage path.

In testimony whereof I have signed my name to this specification on this 27th day of May, A. D. 1926.
